MINING APPARATUS

Charles F. Osgood, Claremont, N. H., assignor to
 Sullivan Machinery Company, a corporation of
 Massachusetts

Application March 2, 1937, Serial No. 128,638

4 Claims. (Cl. 262—28)

This invention relates to mining apparatus, and more particularly to improvements in a coal mining apparatus of the combined kerf cutting and drilling type for cutting kerfs in a coal seam 5 and for drilling blast holes in the coal for receiving blasting charges for breaking down the coal previously cut.

An object of this invention is to provide an improved coal mining apparatus of the combined 10 kerf cutting and drilling type, whereby blast holes may be drilled in the coal seam by drilling means associated with the kerf cutting means, whereby the coal may be drilled either during or subsequent to the kerf cutting operation. Another 15 object is to provide an improved coal drilling means of the type particularly adapted to use with a coal cutting machine, whereby during or subsequent to the kerf cutting operation a plurality of blast holes may be drilled in the coal. 20 Still another object is to provide an improved drilling means particularly adapted to use with a coal cutting machine of the top cutting type, whereby when the coal is being top-cut, blast holes may be drilled in the coal face below the 25 cut wherein and in adjacency to the mine floor. A further object is to provide an improved kerf cutting and drilling apparatus having improved means for mounting the drilling means on the coal cutting machine, whereby the drilling means 30 may be adjusted into different drilling positions with respect to the kerf cutting means. A still further object is to provide in a coal cutting machine of the combined horizontal and shear cutter type, an improved drilling means, whereby blast 35 holes may be drilled in the coal face at various locations with respect to the horizontal and vertical kerfs cut by the kerf cutting means. Yet another object is to provide in a coal mining apparatus of the adjustable kerf cutter type having 40 a kerf cutter adjustable into either horizontal bottom or top cutting positions, an improved drilling means for drilling top holes during the bottom cutting operation and bottom holes during the top cutting operation. A still further object is to provide in a coal cutting machine of the 45 so-called "universal" type having a rotatable cutter head for adjusting the kerf cutter into horizontal top and bottom cutting positions above and below the head axis and vertical shearing positions at either side of the head axis, an improved drilling means, whereby blast holes may be drilled 50 in the coal face at various locations in any cutting position of the kerf cutter. Still another object is to provide an improved coal drill mounted in an improved manner on a coal cutting 55

machine, whereby the drill may be adjusted into different drilling positions about an axis coincident with the axis of rotation of the rotatable cutter head. A still further object is to provide an improved coal drill having an improved adjustable supporting structure, whereby the drill may be readily adjusted into different drilling positions, in an improved manner. These and other objects and advantages of the invention will, however, hereinafter more fully appear in 10 the course of the following description and as more particularly pointed out in the appended claims.

In the accompanying drawings there are shown for purposes of illustration several forms which 15 the invention may assume in practice.

In these drawings—

Fig. 1 is a plan view of a coal mining apparatus in which one illustrative form of the improved drilling means is embodied.

Fig. 2 is a side elevational view of the coal mining apparatus shown in Fig. 1.

Fig. 3 is a front end elevational view of the mining apparatus shown in Figs. 1 and 2, illustrating various positions into which the improved 25 drilling means may be adjusted.

Fig. 4 is an enlarged transverse vertical sectional view taken substantially on line 4—4 of Fig. 1.

Fig. 5 is a detail view in longitudinal vertical 30 section taken substantially on line 5—5 of Fig. 1.

Fig. 6 is a vertical sectional view taken substantially on line 6—6 of Fig. 3, illustrating details of the drilling means.

Fig. 7 is a detail vertical sectional view taken 35 substantially on line 7—7 of Fig. 1.

Fig. 8 is a cross sectional view taken substantially on line 8—8 of Fig. 7.

Fig. 9 is a diagrammatic view showing the improved coal mining apparatus operating in a 40 mine entry and showing various adjusted positions of the improved drilling means.

Fig. 10 is a fragmentary plan view of the forward portion of the mining apparatus shown in Fig. 1, illustrating a modified form of the im- 45 proved drilling means.

Fig. 11 is a detail transverse vertical sectional view taken substantially on line 11—11 of Fig. 10.

Fig. 12 is a view similar to Fig. 10, showing a further modified form of the improved drilling 50 means.

Fig. 13 is a fragmentary side elevational view of the mining apparatus shown in Fig. 12.

Figs. 14 and 15 are diagrammatic views showing the coal mining apparatus in operating po- 55

sition in a mine entry, illustrating different adjusted positions of the improved drilling means.

In the several illustrative embodiments of the improved drilling means, the latter is associated with a coal cutting machine of the combined horizontal and shear cutter type commonly known as a "universal" track cutter, although it will be evident that the several forms of the improved drilling means may be associated with coal cutting machines of various other types. The coal cutting machine, in this particular instance, is of the same general type as that disclosed in my Patent No. 2,007,900, patented July 9, 1935, and generally comprises a portable base mounted on wheels 2 adapted to travel along a mine trackway 3 laid on the mine floor. Mounted on the base, in overlying relation thereon, is a horizontal turntable 4 journaled for rotation in an annular frame 5 adjustably supported by three screw pedestals 6 mounted on the base. Supported on the turntable, and overhanging the annular turntable bearing frame 5 at the forward end of the base, is a horizontal arm structure 7, on which is supported a cutter carrying head 8 rotatable about a horizontal axis extending longitudinally of the arm structure 7. Supported by the rotatable cutter carrying head 8 is a transverse guiding frame 9, in which is slidably guided a supporting frame 10, and pivotally mounted on this supporting frame for swinging movement about an axis at right angles to the head axis, is a plane kerf cutter 11. This kerf cutter is in the form of an elongated plane cutter bar 12 having guided for circulation about its margin an endless cutter chain 13. As shown in Fig. 5, the rotatable cutter carrying head 8 has an annular neck bearing portion 14 journaled for rotation in a bearing frame 15 supported by the arm structure 7. As clearly described in the patent above referred to, supported by the turntable 4 is a motor 16 having its power shaft connected through transmission gearing, including a horizontal shaft 17 journaled within the arm structure 7, a transmission shaft 18 and intermeshing spur gearing 19, for connecting the shafts 17 and 18 in driving relation, and the shaft 18 is operatively connected to the cutter chain for driving the latter, and the shaft 17 drives gearing comprising an internal gear 20 secured to the annular bearing frame 15, for rotating the cutter head. Also driven through the transmission shaft 18 is the mechanism for adjusting the sliding frame 10 along its guiding frame 9 relative to the cutter head frame for adjusting the kerf cutter into parallel cutting planes toward and from the head axis. Supported on the truck frame is a motor 21 having its power shaft connected through transmission mechanism arranged within a transmission housing 22 for driving the truck wheels to propel the apparatus along the mine trackway and for adjusting the screw pedestals 6 for effecting vertical adjustment and universal tilting of the turntable 4 with respect to the portable base. As clearly described in the patent mentioned above, this coal mining apparatus is capable of cutting horizontal kerfs at the floor and roof levels and horizontal kerfs at any intermediate level, and parallel vertical shear kerfs at either side of the head axis; and in any adjusted position of the kerf cutter, the apparatus may be operated to sump the kerf cutter within the coal seam, swing the kerf cutter accurately in its plane and to withdraw the kerf cutter from the coal seam in accordance with the well known arcweld method of

cutting. As the specific structure of the coal mining apparatus does not enter into this invention, other than the particular cooperation thereof with the drilling means, and is clearly described in the above mentioned patent, further detailed description thereof is considered unnecessary.

Now referring to the illustrative embodiment of the improved drilling means shown in Figs. 1 to 9, inclusive, it will be noted that surrounding the neck bearing mounting of the cutter carrying head 8 supported on the arm structure 7 on the turntable 4, is an annular supporting and adjusting frame 25 journaled at 26 on a cylindrical bearing support 27 preferably formed integral with the arm structure 7, for rotation about an axis coincident with the axis of rotation of the cutter carrying head 8. This annular frame 25 is supported on its bearing mounting on the cylindrical support 27 by an annular retaining flange 28 secured to the support 27 and herein formed integral with the cylindrical bearing frame 15 of the rotatable cutter carrying head. The means for rotating the annular frame 25 on its bearing with respect to the support 27 may assume various forms and, in this instance, comprises a worm 29 journaled within a bearing bracket 30 secured to the bottom of the arm structure 7 and meshing with worm gear teeth 31 formed on a sleeve-like portion 32 integral with the annular frame 25. This worm 29 is keyed to a horizontal operating shaft 33 projecting laterally in opposite directions through the opposite sides of the bearing bracket 30 in the manner shown in Fig. 4, and has fixed thereto at its opposite ends, operating handles 34. The teeth of the worm gearing are of the self-locking type and lock automatically the annular frame 25 in its adjusted position on its bearing on the support 27. In this construction, formed integral with the annular frame 25 and projecting laterally therefrom is an arm 35 lying in transverse planes at right angles to the axis of rotation of the rotatable frame 25. Swivelly mounted at 36, in any suitable manner, on the outer extremity of the arm 35 is a support 37, herein, for illustrative purposes, keyed to a horizontal shaft 38 (see Figs. 7 and 8) arranged with its axis parallel with the axis of rotation of the annular supporting frame 25 and journaled at 39 within bearing supports integral with the arm 35. The support 37 may be swung about its swivel mounting on the arm into different angularly related positions with respect thereto, and may be locked in adjusted position by a clamp member 40 splined to the shaft 38 and having its inner surface serrated for engagement with the serrated outer surface of a plate 41 secured to the arm. Secured to the threaded reduced end 42 of the shaft is a nut 43 having an operating handle 44, for pressing the plates together to effect locking. Pivots mounted at 45, in any suitable manner, on the swivel support 37 on an axis arranged at right angles to the swivel support axis, is an elongated arm 46, the arm swingable in planes parallel to a plane including the swivel support axis. Swivelled at 47 on the outer extremity of the arm 46 on an axis at right angles to the arm pivot axis is a support 48, and when the arm is arranged with its longitudinal axis disposed at right angles to the axis of the swiveled support 37, the axis 47 is parallel with the swivel axis 36 of the support 37, as shown in Fig. 3. The support 48 and the arm 46 may be locked in adjusted position about their respective pivotal axes by any suitable lock-

ing means, such as friction locking plates 49 (see Fig. 6) interposed between the opposite faces of the bearing lug on the support and the inner faces of the bearing lugs on the arm, and passing through apertures in the bearing lugs and plates is a shaft 50 keyed to the bearing portions of the arm and having a threaded end 51 on which is threaded an adjusting nut 52 provided with an operating handle 53. When the nut 52 is tightened, the plates are pressed together frictionally to hold the parts in adjusted position. The plates may, if desired, be serrated to provide for firm holding of the parts. Swiveled in a suitable manner on the support 48 at the outer extremity of the arm on an axis at right angles to the axis of the support 48 is a drill casing 54 of a coal drill generally designated 55. The drill casing has an annular bearing flange 56 rotatably mounted in a circular bearing recess 57 on the support 48 and retained therein by an annular retaining ring 58. Any suitable locking means may be employed for locking the swiveled drill casing to the support 48, such as a clamping screw 60 having an operating handle 61 and engaging the serrated outer surface of the annular bearing flange 56.

The coal drill 55 may be of any conventional and well known form, and in this instance comprises a motor 62 having its power shaft coupled to a drive shaft 63 suitably journaled within the drill casing. Keyed to the shaft 63 are spur gears 64 and 65 of different tooth ratio meshing with gears 66 and 67, respectively. The gears 66 and 67 are connected in driving relation with the drill feeding and rotation mechanism under the control of friction clutches, in the same general manner as that disclosed in the Holmes Patent No. 1,903,648, patented April 11, 1933. The drill rotating and feeding stem 68 has a chuck 69 for receiving the shank of a usual auger drill steel 70 (see Fig. 6). When both clutches of the drill feeding and rotating mechanism are applied, the drill steel may be fed forwardly at a slow drilling speed, and when one or the other of the clutches is released, the drill steel may be fed either forwardly or rearwardly at a relatively high positioning speed.

The mode of operation of this embodiment of the invention will be clearly apparent from the description given. The drilling means may be transported about the mine from one working place to another while the drill is resting on the top of the turntable or in any other convenient manner. When the working place is reached, the cutter carrying head 8 of the coal cutting machine may be adjusted to position the cutter bar 12 into any desired horizontal or vertical cutting plane between the mine roof and mine floor and between the ribs, and the cutter bar may be sumped in, swung arcuately in its plane and withdrawn from the coal seam in accordance with the arcwall method of cutting, in a manner well known to those skilled in the art. When it is desired to cut a horizontal kerf at or near the level of the mine floor, the cutter head 8 is disposed in the position shown in Figs. 1, 3 and 9, and the bar adjusting mechanism is operated to adjust the sliding frame 10 downwardly along the guiding frame 9 to lower the cutter bar into its bottom cutting position. During the bottom cutting operation, the operator may manipulate the handle 34 of the worm rotating shaft to adjust, through the worm gearing, the annular supporting frame 25 of the drill supporting structure about its axis relative to the cutter head and turntable to locate the drill in a position to drill

blast holes at or near the mine roof and between and at the ribs of the entry. It is possible to operate the drill to effect its drilling function either during the bottom cutting operation or subsequent to the bottom cutting operation. The drill may be swung into positions at either side of the coal cutting machine by rotation of the annular supporting frame, and the drill adjusted about the various pivotal axes of the supporting structure in the manners indicated in dotted lines in Fig. 10, 3, to locate the drill to drill blast holes in any desired position in the coal face or in either rib of the entry. When it is desired to cut a horizontal kerf at or near the roof level, the cutter head 8 of the coal cutting machine is rotated 15 about its axis to locate the cutter bar in horizontal top cutting position above the head axis. During the top cutting operation, the annular supporting frame 25 of the drill supporting structure may be rotated relative to the cutter head 20 and turntable to locate the drill below the head axis in position to drill blast holes near the mine floor and between and at the ribs of the entry. If desired, the screw pedestals 6 of the turntable supporting means of the coal cutting machine 25 may be adjusted to elevate the turntable 4 to provide more space beneath the cutter head, thereby to facilitate adjustment of the drill supporting structure during bottom hole drilling. During the vertical shear cutting operation at 30 either side of the head axis, the drill may be adjusted to drill blast holes at either side of the vertical shear cut and at or near the roof and floor levels.

In the illustrative embodiment of the invention shown in Figs. 10 and 11, the drill arm and supporting structure, the drill, and the annular supporting frame surrounding the neck of the rotatable cutter head 8 are substantially the same as those above described. In this instance, however, the annular drill supporting frame is formed with a transverse guideway 75 slidably receiving a block 76 on which is swivelly mounted at 77 on an axis lying in a transverse vertical plane at right angles to a plane including the axis of rotation of the annular drill supporting frame and the cutter frame, a support 78. In other words, the swivel axis 77 of the support is perpendicular to the plane of the sliding block guideway 75, as shown in Fig. 11. The support 78 is pivotally mounted on a shaft 79 preferably formed integral with the sliding block 76. Journaled on the guide frame in parallelism with the guideway is an adjusting screw 80 threaded at 81 within the sliding block and provided, at its opposite ends, with operating handles 82. Any suitable means may be employed for locking the swivel support 78 in its adjusted position, such as a serrated clamp 83 similar to the clamp shown in Figs. 7 and 8 of the form of the invention above described. Secured to the swivel support 78 is an elongated arm 84 on which the drill 55 is swivelly mounted, in the same manner as that shown in Fig. 6. It will thus be seen that the drill has not only the adjustments of the form of the invention above described, but may also be adjusted transversely of the annular drill supporting frame simply by adjusting the adjusting screw and moving the sliding block along the guideway. The guideway may, of course, be adjusted, by 70 rotation of the annular drill supporting frame about the head axis, into positions below and at either side of the cutter head axis, and the drill adjusted into various drilling positions, some of which are indicated in dotted lines in Fig. 10. 75

Otherwise the mode of operation of this form of the invention is the same as that above described.

In the illustrative embodiment of the invention shown in Figs. 12 to 15, inclusive, the coal cutting machine is the same as that shown in Figs. 1 and 2. In this instance, however, the drill is supported by the rotatable cutter head 8 at the side of the latter opposite from the cutter bar and wholly independently of the cutter bar, so that when the cutter bar is in top cutting position, the drill is supported beneath the cutter head, and when the cutter bar is in bottom cutting position the drill is supported above the cutter head. Mounted for rotation on the cutter head frame about an axis alined with the pivotal axis of the cutter bar 12 is a turntable 86, a frame 87 secured to the head frame providing a journal for the turntable. The turntable may be locked in its adjusted position to the frame 87 and cutter head in any suitable manner, such as by a locking screw 88 provided with an operating handle 89 and engageable with the turntable. Swiveled at 90 on the turntable 86 on an axis at right angles to the turntable axis, is a support 91 carrying an elongated arm 92 on which the drill 55 is swivelly mounted in a manner similar to that shown in Fig. 6. The swivel support 91 may be locked in its adjusted position relative to the turntable by a serrated clamp 93 similar to that shown in Figs. 7 and 8, and the drill swivel clamp 94 at the outer extremity of the arm may be the same as that shown in Fig. 6.

The mode of operation of this form of the invention is as follows: The coal cutting machine is operated in the same manner as that above described in connection with the other forms of the invention, and when the cutter head 8 is in the bottom cutting position shown in Fig. 14, or the top cutting position shown in Fig. 15, the cutter bar may be sumped in, swung arcuately in its plane and withdrawn from the coal face in an identical manner. During bottom cutting, the drill is disposed in the manner shown in Fig. 14, above the cutter head, and may be adjusted to drill top holes in the coal face at any desired location at or near the roof level and in the ribs. During top cutting, the drill is disposed beneath the cutter head, as shown in Fig. 15, and may be adjusted to drill bottom holes in the coal face at any desired location at or near the floor level and in the ribs. By the provision of the swivel supporting structure for the drill, the latter may be adjusted into positions to drill blast holes in the coal face at different inclinations or in parallelism at different locations and in either rib, and when the cutter head is turned into shear cutting position, holes may be drilled in the coal face at any desired point at either side of the vertical kerf, near the roof level or the floor level.

It is to be understood that this invention is not to be limited to the particular drill and supporting structure shown, so long as the drill may be adjusted about the axis of the cutter head either with or independently of the cutter head, for drilling during the cutting operation or subsequently thereto. It will be evident that power rotation may be provided for rotating the drill supporting structure about the head axis, and in all forms of the invention the drill may be driven by a motor supported independently of the drill supporting structure through connections extending through the supporting structure or by flexible shafting in an obvious man-

ner. Also the various forms of locking clamps may be substituted by other appropriate forms, and, in certain cases, the drill supporting structure may be hydraulically adjusted and locking effected by hydraulically operated clamps, all in a manner well known in the art.

As a result of this invention, it will be noted that an improved coal mining apparatus of the combined kerf cutting and drilling type is provided for cutting kerfs and drilling blast holes at any desired location in the coal seam. It will further be evident that an improved coal mining apparatus of the combined kerf cutting and drilling type is provided, having drilling means mounted on the coal cutting machine, whereby the coal may be drilled either during or subsequent to the kerf cutting operation. It will still further be evident that by the provision of the improved adjustable supporting structure for the drill and the improved manner of mounting the drill on the coal cutting machine, it is possible to quickly adjust the drill to drill holes at any desired location in the coal face and either rib of the mine entry. Other uses and advantages of the improved coal mining apparatus will be clearly apparent to those skilled in the art.

While there are in this application specifically described several forms which the invention may assume in practice, it will be understood that these forms of the same are shown for purposes of illustration and that the invention may be further modified and embodied in various other forms without departing from its spirit or the scope of the appended claims.

What I claim as new and desire to secure by Letters Patent is:

1. In a mining apparatus, the combination with a coal cutting machine comprising a rotatable cutter head having its neck rotatably mounted in a bearing on the machine and carrying a kerf cutter, said cutter head rotatable to adjust said kerf cutter into different cutting planes about the head axis, of a coal drill, and an adjustable supporting structure mounted on the front end of said cutting machine in adjacency to the cutter head neck for supporting said coal drill independently of said kerf cutter so that the drilling operation may occur simultaneously with the kerf cutting operation, said supporting structure comprising a member rotatably mounted on and surrounding the cutter head neck bearing mounting, and an arm structure pivotally mounted on said rotatable member, said supporting structure supporting the coal drill for adjustment relative to the coal cutting machine into horizontal drilling positions above and below the cutter head to drill horizontal holes in the coal face near the mine roof or mine floor, said supporting structure including elements for supporting said coal drill and through which the drill is connected to the cutting machine during adjustment thereof into any of aforesaid drilling positions.

2. In a mining apparatus, the combination with a coal cutting machine comprising a horizontal support swingable horizontally about a vertical axis and a cutter head having its neck rotatably mounted in a bearing on said horizontally swingable support and carrying a kerf cutter, said cutter head rotatable to adjust said kerf cutter into different cutting planes about the head axis relative to said support, of a coal drill, and an adjustable supporting structure mounted at the forward end of said cutting machine between said

horizontally swingable support and said cutter head in adjacency to the cutter head neck for supporting said coal drill on the cutting machine independently of the kerf cutter so that the drilling operation may occur simultaneously with the kerf cutting operation, said supporting structure supporting said coal drill for adjustment relative to the coal cutting machine into horizontal drilling positions above and below the cutter head to 5
drill horizontal holes in the coal face near the mine roof or mine floor, said supporting structure including a supporting member rotatably mounted on and surrounding the cutter head bearing mounting and an adjustable support carried by said rotatable member and on which said coal drill is mounted for supporting the coal drill and through which the drill is connected to the cutting machine during adjustment thereof into any of aforesaid drilling positions.
10
20
3. In a mining machine, the combination with a coal cutting machine having a rotatable cutter head carrying a kerf cutter and rotatable to adjust said kerf cutter into different cutting planes about the head axis, of a coal drill, and an adjustable supporting structure mounted on the front end of said cutting machine in adjacency to the cutter head for supporting said coal drill on the cutting machine independently of the kerf cutter so that the drilling operation may 15
25
30
35 occur simultaneously with the kerf cutting operation, said supporting structure supporting said coal drill for adjustment relative to the cutting machine into horizontal drilling positions at the opposite sides of said cutter head and above and below the cutter head to drill horizontal holes in the coal face at either rib and near the mine floor and mine roof, said supporting structure in-

cluding a guide frame providing a transverse guideway, means for adjusting said guide frame into positions above and below the cutter head axis, and a support mounted on said guideway for adjustment therealong and on which said coal drill is mounted for supporting said coal drill and through which the drill is connected to the cutting machine during adjustment thereof into any of aforesaid drilling positions.
5

4. In a mining apparatus, the combination with a coal cutting machine having a kerf cutter adjustable relative to the coal face into horizontal top cutting and horizontal bottom cutting positions near the roof and floor levels, of a coal drill, and an adjustable supporting structure mounted 10 at the front end of said cutting machine in adjacency to the rear end of said kerf cutter for supporting said coal drill on the cutting machine independently of said kerf cutter so that the drilling operation may occur simultaneously with 15 the kerf cutting operation, said supporting structure supporting said coal drill for adjustment relative to the cutting machine into drilling positions near the mine floor and near the mine roof and at either side of the machine, said supporting structure including an annular supporting 20 frame journaled on said cutting machine about a horizontal axis extending longitudinally of the machine and a drill supporting structure adjustably mounted on said annular frame and adjustable upon rotation of the latter into different drill supporting positions relative to the cutting machine for supporting said coal drill and through which the drill is connected to the cutting machine during adjustment thereof into any of 25
30
35 aforesaid drilling positions.
35

CHARLES F. OSGOOD.
